W. L. HUMASON, OF NEW BRITAIN, CONNECTICUT.

Design No. 3,373, dated February 16, 1869.

DESIGN FOR A LATCH.

The Schedule referred to in these Letters Patent and making part of the same.

To all whom it may concern:

Be it known that I, W. L. HUMASON, of New Britain, in the county of Hartford, and State of Connecticut, have originated and designed a new Design for a Latch, of which the following is a full, clear, and exact description, reference being had to the accompanying drawings, making a part of this specification, which drawing is a perspective view of my invention or production.

My invention is configured by several square and rectangular-shaped panels, the surface of which panels is covered with bars, or alternate ribs and channels, and bordered by plane ledges.

The latch *a* is in shape of a cross, and contains four panels, the bars of which are lengthwise with the longest part of the cross.

Near the centre and end of the cross-shaped latch *a*, is a square plane surface, which is partially covered by the knob *b* and rivet *c*.

The frame *d* of the latch is T-shaped, and the four

screw-holes *e* are in the centre of four square panels at the respective corners of frame *d*.

Similar panels and screw-holes, *e*, are on each end of the base of the catch *g*, which is of rectangular shape, and of the same length as the cross-part of the frame *d*, and when in place on the door, it helps to widen out and partially form the cross-part of the T-shaped frame *d*.

The panels 1 have the bars parallel to the cross-part of the T, while the panels 2 have the bars parallel with the upright portion of the T.

The latch is placed on the door, with the cross-part of the T in an upright position.

What I claim as new, and desire to secure by Letters Patent, is—

The design for a latch, herein shown and described.

W. L. HUMASON.
